US00D770446S

(12) **United States Design Patent** (10) Patent No.: **US D770,446 S**
Cho et al. (45) Date of Patent: ** Nov. 1, 2016

(54) **ELECTRONIC DEVICE**

- (71) Applicant: **Samsung Electronics Co., Ltd.**, Suwon-si, Gyeonggi-do (KR)
- (72) Inventors: **Chul-Yong Cho**, Seoul (KR); **Dae Kyung Ahn**, Seoul (KR); **Sangmin Hyun**, Seoul (KR); **Eun Vit Chung**, Seoul (KR)
- (73) Assignee: **SAMSUNG ELECTRONICS CO., LTD.** (KR)
- (**) Term: **15 Years**
- (21) Appl. No.: **29/545,260**
- (22) Filed: **Nov. 11, 2015**

Related U.S. Application Data

- (63) Continuation of application No. 29/462,289, filed on Aug. 1, 2013, now Pat. No. Des. 745,001.

(30) **Foreign Application Priority Data**

Feb. 1, 2013 (KR) 30-2013-0005876

- (51) LOC (10) Cl. **14-02**
(52) U.S. Cl. **USPC D14/341**

(57) **CLAIM**

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is the top plan view thereof;

FIG. 7 is the bottom plan view thereof;

FIG. 8 is a perspective view thereof, with the electronic device being folded;

FIG. 9 is a left side view thereof, with the electronic device being folded; and,

FIG. 10 is a back perspective view thereof, with the stand popped out.

The broken lines shown in the drawings illustrate portions of the electronic device that form no part of the claimed design.

1 Claim, 9 Drawing Sheets
